G. H. RUSSELL

IRONING BOARD

Filed June 25, 1923

UNITED STATES PATENT OFFICE.

GEORGE H. RUSSELL, OF FLORENCE, ALABAMA.

IRONING BOARD.

Application filed June 25, 1923. Serial No. 647,648.

To all whom it may concern:

Be it known that I, GEORGE H. RUSSELL, a citizen of the United States, residing at Florence, in the county of Lauderdale and State of Alabama, have invented a new and useful Ironing Board, of which the following is a specification.

This invention has reference to ironing boards or tables, the primary object of the invention being to provide a combined ironing board and table, the structure being such as to permit the supporting legs thereof to be readily folded to a position in proximity to the ironing board to require the minimum amount of space in storing.

Another object of the invention is to provide supporting legs of a construction wherein pressure on the ironing board will tend to create a binding action between the leg sections to lend rigidity to the structure.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of an ironing table constructed in accordance with the present invention, parts thereof being broken away;

Figure 2 is a bottom plan view of the table showing the legs in their inactive or folded position;

Figure 3 is a detail view disclosing the means for locking the legs in their folded positions.

Referring to the drawing in detail, the reference character 5 designates the table or ironing board which may be formed of any suitable material and provided with pairs of spaced ears 6 arranged on the under side of the table 5.

The forward legs are indicated at 7 and have their inner ends pivotally supported between the ears 6 as clearly shown by Figure 2 of the drawing, pins 8 disposed through the ears of each pair to secure the

legs 7 thereto. At the free ends of the legs 7 is secured a brace bar 9 which, together with the brace bar 10 disposed substantially intermediate the ends of the legs 7, holds the legs 7 in proper spaced relation with each other.

Legs 11 also have their inner ends pivotally supported between the ears 6 and held therebetween by means of the pins 8, the outer or free ends of the legs 11 being secured in proper spaced relation with respect to each other by means of the brace bars 12. A brace bar 13 is disposed substantially intermediate the ends of the legs 11 and hold the legs against movement with respect to each other at this point.

As shown, these legs 11 are relatively long as compared with the legs 7 and are designed to extend at angles with respect to the table 5, the lower outer edges of the legs 11 being beveled to properly engage the surface on which the table is supported.

Cooperating with the brace bar 10 are the pivoted bars 14 that are held in proper spaced relation at their outer ends, by means of the bar 15 disposed therebetween, the inner ends of the bars 14 being connected as shown by Figure 2 of the drawing and adapted to engage the under surface of the table 5.

These bars 14 have pivotal connection with the legs 11, as by means of the rod 16 so that movement of the legs 11 will be transmitted to the bars 14. A pair of spaced ears 17 are also secured to the under side of the table 5, and between the ears 17 is positioned a link 18 that has pivotal connection with the bars 14 as at 19.

Formed in the bars 14 at points adjacent to the free ends thereof, are notches 20 that accommodate one edge of the bracing bar 10 so that pressure on the table 5 will result in a movement of the bars 14 to create a binding action between the bars 14 and bracing bar 10, to insure against movement of the legs with respect to the table.

In order that the leg members may be held in their folded positions, the leg members 7 that overlie the leg members 11 and bars 14, are provided with a hook member 21 adapted to be positioned in the keeper 22 secured to the under surface of the table 5. Due to this construction it will be noted that when the legs of the iron-

ing table are moved to their folded positions, it is impossible for the legs to accidentally swing to an open position.

What is claimed as new is:—

- 5 In an ironing table, a table section, vertical leg members pivotally supported under the table section, an intermediate cross member connecting said leg members, leg members pivotally connected to the table section
10 and disposed at oblique angles with respect to the first mentioned leg members, bars having pivotal connection with the obliquely disposed leg members at points intermediate the ends thereof, a link member secured to
15 the under surface of the table section and

having pivotal connection with the bars, the upper ends of the bars adapted to engage the under surface of the table section, and the opposite ends of the bars adapted to engage the lower side of said cross bar to 20 set up a binding action between the bars and first mentioned leg members when pressure is directed to the table section.

In testimony that I claim the foregoing as my own, I have hereto affixed my signature in the presence of two witnesses.

GEORGE H. RUSSELL.

Witnesses:

PAULINE DARMER,

GRACE PRESLEY.
